UNITED STATES PATENT OFFICE.

JOSEPH R. LANCASTER, OF NEW YORK, N. Y., ASSIGNOR TO JORDAN L. MOTT, OF SAME PLACE.

DESIGN FOR WASH-BASIN.

Specification forming part of Design No. 7,464, dated June 2, 1874; application filed May 1, 1874.
[Term of Patent 7 years.]

CASE B.

To all whom it may concern:

Be it known that I, JOSEPH R. LANCASTER, of the city, county, and State of New York, have invented a new and original Design for a Wash-Basin, of which the following is a specification:

The nature of the design is fully represented in the accompanying printed illustration.

The same relates to the ornamentation of the conical or spherical bowl C, which is provided with a projecting rim, a, around its truncated lower end, while its body is orna-

mented by fan-shaped figures formed by a bead or astragal molding, e, as shown.

I intend the back A and top B of the sink to form the subject of separate Letters Patent.

What I here claim is—

The design for the ornamentation of the bowl C, formed by the rim a and molding e, as shown.

Witnesses: JOSEPH R. LANCASTER.
JOHN REID,
RUD. MAGNUS.
